HEEL BUILDING MACHINE

William Hubbard, Dolgeville, N. Y., assignor to
 United Shoe Machinery Corporation, Paterson,
 N. J., a corporation of New Jersey

Application January 28, 1937, Serial No. 122,810

8 Claims. (Cl. 12—50)

This invention relates to heel building machines and is exemplified herein as embodied in a machine of the type in which heel lifts are assembled by hand in a form where the assembly is subjected to pressure, applied by power, and held under pressure while one or more heel building nails is, or are, driven.

It is the object of the invention to provide an improved machine of this type the use of which will insure the production of accurate heels of high quality with a minimum requirement for skill and experience on the part of the operator.

With this in view, the illustrated machine embodies an improved heel form comprising a set of heel engaging jaws which are yieldingly bodily compressible in response to downward pressure. This eliminates inaccuracies in lift alignment which are liable to occur with jaws designed to yield outward when the lifts are forcibly pressed down in the form, while retaining the advantage that the edges of the lifts are not objectionably marked by their pressure against the jaws. Further insurance against detrimental deformation of the edges of the lifts is provided by so hanging the jaws upon pivotally mounted arms that as the jaws are depressed their upper ends move outward and enlarge the upper portion of the form proportionately as the larger lifts of the heel are pressed down into it.

Further features of improvement relating to the means for operating the pressure applying and nail driving mechanism, and other features and advantages of the invention will be better understood and appreciated from the following detailed description of an illustrative machine, to be read in connection with the accompanying drawings, in which

Fig. 1 is a view in front elevation of a heel building machine embodying the invention;

Fig. 2 is a view partly in side elevation and partly in vertical section;

Fig. 3 is a plan view of the machine with the presser foot removed;

Fig. 4 is a view in rear elevation of the spring operated cam control mechanism for applying pressure to a built-up heel;

Fig. 5 shows a detail of the clutch control mechanism;

Fig. 6 is a view in elevation of a built-up heel after the heel building nail has been driven;

Fig. 7 is a view in front elevation of the paste applying mechanism;

Fig. 8 is a view in vertical section through the heel building form, taken upon the line VIII—VIII of Fig. 3, and

Fig. 9 is a vertical sectional view of a detail of the form jaw mounting, taken upon the line IX—IX of Fig. 3.

In the drawings, 10 indicates a stationary base or frame to which may be secured by bolts 12 5 the base member 14 of a heel press, for example as that described and claimed in my copending application Serial No. 122,811, filed concurrently herewith.

Supported upon the top of the frame 10 is a 10 table 16 upon which is mounted the heel building form to be described hereinafter. In the use of the machine a series of lifts of graded sizes are pasted, assembled in the form, pressure is applied to the pile of lifts and a heel building nail 15 is driven through them. The heel 18 resulting from this operation is illustrated in Fig. 6.

The mechanism for applying pressure to the assembled lifts and driving the heel building nail through is controlled and operated by concentric, 20 horizontal cams 20 and 22, respectively. These cams are fixed to each other by screws 24 and constitute a rotary unit having a hub 26 provided with upper and lower bushings 28, 30 which are journaled upon an upright shaft 32 (see Fig. 2). 25 The shaft 32 rotates in stationary upper and lower bearings 34 and 36 respectively and has secured to it near its lower end a bevel gear 38 which is driven by a pinion 40 secured to a drive shaft 42 carrying tight and loose pulleys 44, 46 30 to receive a driving belt from any suitable source of power.

The cam unit 20, 22 is supported by a ball bearing 48 which runs in a stationary raceway 50 mounted in the base of the machine and the 35 cam unit may be connected at will to the shaft 32, which runs continuously when the driving belt is upon the tight pulley. The mechanism for effecting this connection comprises a sleeve 52 which loosely surrounds the shaft 32 and is 40 coupled at 54 to the hub 26 by a series of interlocking notches and projections in such a manner that the sleeve 52 can slide vertically relatively to the hub but cannot rotate relatively thereto. A spring 56 surrounding the shaft 32 45 tends at all times to raise the sleeve and cause teeth 58, which are cut in its upper end, to engage similar teeth 60, which are cut in the lower end of a clutch member 62 pinned to the shaft 32, to effect a driving connection between the 50 shaft and the cam unit.

Resting upon and supported by the cam 20 is a cam roll 64 carried by the lower end of a slide 66 which is guided for vertical movement in ways formed in the rear face of a vertical 55

stationary web 68 which extends from side to side of the frame 10.

Projecting rearward from the slide 66 are brackets 70 in which are secured, by set screws 5 72, the lower ends of a pair of vertical rods 74 the upper ends of which are guided in bushings 76 adjustably threaded through the top of the machine frame 10. The rods 74 are surrounded by heavy pressure springs 78 the tension of which can be adjusted by turning the bushings 76 and which cause the cam roll 64 to bear down heavily in a direct line upon the cam 20.

In the upper end of the slide 66 is formed a bearing 80 in which is swiveled the lower end of 15 a rotatable standard 82 which is guided for vertical sliding and rotary movement by a bearing 84 bolted down upon the top of the machine frame. A collar 86, pinned to the lower end of the standard 82, has a downwardly projecting lug 88 which limits the rotary movement of the 20 standard 82 relative to the slide 66.

To the upper end of the standard 82 is secured a block 90 which extends forward and provides a bearing for an adjusting screw 94 which is 25 threaded into a presser foot carrier 96 splined at 81 to the standard 82 so that it can be adjusted vertically thereon but is constrained to rotate therewith. A handle 98 enables the operator to swing the presser foot carrier and the 30 standard about the axis of the latter within the limits permitted by the lug 88.

Mounted upon the carrier 96, with a bolt and slot connection 100 to permit forward and rearward adjustment, is a presser foot supporting 35 arm 102 to which is pivoted at 104 a presser foot 106 conforming approximately to the shape of the heel to be built. A screw 108 threaded through the support 102 and bearing upon the top of the presser foot provides for angular 40 adjustment of the latter around the pivot 104 and helps sustain the pressure applied to the heel. It will be apparent that when a high portion of the cam 20 is beneath the roll 64 the pressure springs 78 will be compressed and the slide and 45 presser foot carried thereby will be raised to permit a heel to be assembled in the form. When a low portion of the cam comes beneath the roll 64 the springs 78 are permitted to expand and apply pressure to the heel and to hold it while 50 the heel building nail is driven.

The driving of the heel building nail is accomplished by a nail driver 110 secured in a driver block 112 which is, in turn, secured in a driver head 114 mounted upon the face of a vertically 55 movable slide 116 in the lower end of which is journaled a cam roll 118 engaging the cam 22. The driver head 114 is secured to the slide 116 by a bolt 120 which passes through a slot 122 in the head and is threaded into the slide, an adjustable supporting screw 124 serving to adjust 60 the vertical position of the driver and to transmit the driving force from the slide 116 to the driver head 114.

The upper end of the nail driver 110 is guided 65 in a nail tube 126 of which the upper end is normally flush with the surface of the heel forming table 16 and the lower end is mounted in a plate 128 which is slideable upon vertical studs 130 screwed into the frame 10, as best shown in Fig. 8. Springs 132 normally hold the plate 128 down against the heads of the studs but permit it to yield upward when struck by the driver block 112 which will be so adjusted that it will, near the 70 end of its upward movement, engage the plate 75

128 and elevate the nail tube 126 sufficiently to loosen the heel from the form table 16.

The heel form comprises a breast block and four side jaws. The breast block, which is seen at 134, has a rearwardly extending base portion 136 which may be adjusted toward the front or the rear of the form table and held in the adjusted position by clamping plates 138 tightened by screws 140.

The following description will apply to any one 10 of the four side jaws of the form. A base plate 142, resting upon the form table 16, is provided with pins 144 extending downward into a guide slot 146 formed in the table and a bracket member 148 is held down upon the base plate by a 15 bolt 150 which passes through a slot 152 in the base plate and through the slot 146 in the table 16 against the under side of which the head of the bolt bears. A vertical T-slot 154 in an upright portion 156 of the bracket 148 receives the 20 head 158 of a bolt 160 by means of which a slotted block 162 is secured at any desired height upon the face of the upright portion 156.

Pivoted at 164 in the slot in the block 162 is an arm 166 sustained by a spring 168 and having 25 pivoted in its free end at 170 the upper end of a heel engaging jaw 172, the lower end of which extends into an opening 174 through the table 16. The end portion of the plate 142 is formed with a notch 176 which acts as a guide for the rear 30 edge of the jaw 172 when the jaw is depressed by downward pressure, against the tension of the spring 168.

From the foregoing, it will be apparent that 35 the heel form may be readily adjusted to heels of all sizes and shapes. By loosening the bolt 160 the block 162, carrying the pivot 164, may be adjusted vertically to vary the depth of the form. By loosening the bolt 150 each jaw unit may, as a whole, be adjusted along the slot 146 radially 40 of the form and also, by relative movement of the bracket member 148 and the base plate 142, the inclination of the heel engaging jaw 172 may be varied as desired without affecting the ability of the jaw to yield downward against the tension 45 of its supporting spring 168. Since the pivot 164 is spaced above the table 16 a distance equal to the depth of the form, the upper end of the jaw, when it is depressed, will move slightly outward and the upper portion of the form will be enlarged proportionately as the larger, upper lifts of the heel are pressed down into it, thus avoiding 50 detrimental pressure of the edges of the jaws upon the edges of the lifts.

By reason of the swivel connection at 80 between the standard 82 and the slide 66, the presser foot 106 may readily be swung aside from over the form to afford a clear, unobstructed space in which the operator can assemble the heel lifts, after inserting a nail in the nail tube 126. After 55 the lifts are assembled in the form the operator grasps the handle 98 and swings the presser foot over the form ready to be lowered by power to apply pressure to the assembled lifts. The engagement of the clutch members 52 and 62 to 60 start the power operation of the machine is controlled by a starting handle 178 (see Figs. 1, 3 and 5) affixed to the upper end of an upright shaft 180 to the lower end of which is also affixed a 65 swinging arm 182. Secured in the free end of the arm 182 is a downwardly projecting pin 184 which engages in a recess in a slide 186 which is horizontally movable in a bearing 188 supported by the frame 10 and having its axis arranged to intersect the axis of the shaft 32. 70 75 95

A compression spring 190, the tension of which is adjustable by means of a screw 192, tends continuously to move the slide 186 toward the shaft 32 but can be compressed by swinging the handle 5 178 in a direction to cause the slide to be retracted.

At the end of the slide 186 a roll 194 is loosely mounted upon a pin 196 which is secured in the slide and has a frusto-conical head 198. The roll 10 194 is adapted to engage in a cam slot 200 formed in the sleeve 52 and so shaped as automatically to cause depression of the sleeve against the force of the spring 56 to disengage the clutch teeth 58 from the clutch teeth 60 when the cam unit 20, 15 22 has rotated to the position which it should occupy when the machine is stopped. When the starting handle 178 is moved the roll 194 is retracted from the cam slot 200 and the spring 56 immediately causes engagement of the clutch and 20 rotation of the cam unit through one revolution. In order to prevent this from occurring if the presser foot is not over the heel form and in proper register with the heel blank therein, a projection 202 is provided upon the starting handle 25 178 and arranged to engage the head of a screw 204 adjustably threaded into the end of a sliding pin 206, the screw being secured in its adjusted position in the pin by lock nut 208. The pin is guided for sliding movement in a horizontal guide 30 210 against the force of a compression spring 212 which aids in returning the starting handle 178 to inoperative position when it is released.

The tip of the pin 206 is adapted to enter a vertical slot or keyway 214 formed in the standard 35 82 when the presser foot is over the heel form but not when it is in any other position. Consequently the projection 202 and the pin 206 constitute a safety lock preventing the starting of the machine except under proper conditions.

40 Mounted at the right-hand side of the machine is a paste tank 216 in which rotates, upon a shaft 218, a lower paste applying roll 220. Slotted uprights 222 arising from the sides of the tank 216 afford guides for an upper paste applying roll 224 45 which is normally drawn down into contact with the lower roll 220 by springs 226 which are capable of yielding to permit a heel lift to pass between the rolls. Paste is picked up by the lower roll and transferred to the upper roll when the two 50 are in contact. When the operator passes a lift between the rolls, as shown at 228 in Fig. 7, both sides of the lift are coated uniformly with paste and in the ordinary operation of heel building the alternate lifts of heels will be thus pasted, 55 the intermediate lifts being left dry.

The lower paste roll shaft 218 is coupled at 230 to the hub of a gear 232 which is driven by a pinion 234 fixed upon a shaft 236 journaled in bearings 238, 240 upon a bracket 242 bolted to the 60 frame 10 of the machine. The shaft 236 is driven continuously from the shaft 42 by a sprocket chain 244.

At the under side of the cam 22, and integral therewith, there is a cam 92 which is designated 65 by the same reference numeral in my copending

application Serial No. 122,811, hereinbefore referred to, and serves to operate the heel press described and claimed in that application.

Having described my invention, what is claimed as new and is desired to be secured by Letters Patent of the United States is:

1. In a heel building machine, an upwardly open heel form comprising a stationary table and a plurality of heel engaging jaws which extend upward from the table and are yieldingly compressible bodily relatively to the table in response to downward pressure upon said jaws. 10

2. In a heel building machine, a heel form comprising a heel engaging jaw which is yieldingly compressible in response to downward pressure, 15 and means for moving the upper portion of the jaw outwardly of the form when the jaw is depressed.

3. In a heel building machine, a horizontal, pivotally mounted, spring supported arm, a heel form jaw pivotally suspended from said arm, and a normally stationary guide engaging the back of the jaw below the arm. 20

4. In a heel building machine, a heel form comprising a plurality of heel engaging jaws which are yieldingly compressible in response to downward pressure and means for causing the upper portions of all the jaws to move outward, to enlarge the upper portion of the form, when the jaws are depressed. 25

5. In a heel building machine, a heel form comprising a table which constitutes the bottom of the form, a plurality of radially disposed arms each having its outer end pivotally supported about the table at a distance at least equal to the depth of the form, and a heel form jaw pivoted to the inner end of each arm and extending downward into the table. 35

6. In a heel building machine, a heel form, a presser foot for applying pressure to a heel in the form, a vertically movable slide carrying the presser foot, a horizontally rotatable cam directly supporting the slide, and a pressure spring forcing the slide downward upon the cam. 40

7. In a heel building machine, a heel form, a presser foot for applying pressure to a heel in the form, a vertically movable slide carrying the presser foot, a horizontally rotatable cam positioned beneath and directly in line with the slide, a pressure spring forcing the slide downward upon the cam, a second cam concentric with the first, a second slide bearing upon the second cam and movable parallel to the first slide, and a nail driver carried by the second slide. 45 50

8. In a heel building machine, a heel form, a pair of concentric cams rotatable about a vertical axis, a pair of parallel, vertically movable slides resting directly upon said cams respectively, a nail driver carried by one of the slides and positively actuated upward by the corresponding cam, a pair of pressure springs bearing down on the other slide, and a presser foot carried by said other slide and operable to apply spring pressure downward upon a heel in the form. 55 60

WILLIAM HUBBARD. 65
